UNITED STATES PATENT OFFICE

NATHAN SULZBERGER, OF NEW YORK, N. Y.

SHAVING PREPARATION

No Drawing.

Application filed May 12, 1926. Serial No. 108,694.

This invention relates to new and improved shaving preparations which contain a styptic in regulated amount incorporated therein.

In my prior application Serial No. 625,414, filed March 15, 1923, I have described and claimed certain new soap preparations containing phenol-esters of higher fatty acids containing more than eleven carbon atoms in the fatty acid molecule.

10 The present invention relates to improved shaving preparations which are free from such phenol-esters of higher fatty acids, but which nevertheless contain a small and regulated amount of a styptic incorporated therein.

15 The shaving preparations of the present invention may be shaving soaps or shaving soap preparations containing mainly soap as their basis or they may be other preparations containing only small amounts of soap or free

20 from soap and containing other shaving ingredients. In addition to such usual shaving soap or shaving preparation ingredients I incorporate a small amount of a styptic, such as adrenalin, or other styptic, and I regulate

25 the amount of adrenalin so that it will impart to the shaving preparation a mild astrin-gent or styptic action which will be suffi-
cient to prevent or stop bleeding, which may be caused accidentally by a cut or by injury

30 to a sensitive skin. A small amount of adre-nalin is sufficient for this purpose, although other styptic materials may be similarly used in small and regulated amount.

The styptic should be compatible with the 35 ingredients of the shaving preparations, that is, it should not react objectionably with them to interfere with the desired action of the preparation, or of the styptic.

Adrenalin can be used in various forms, 40 both natural or synthetic, such as in the form of its salts with either inorganic or organic acids, including salts with fatty acids, which will readily blend with the other ingredients of the shaving preparation.

45 Salts such as the hydrochloride, borate, benzoate, or salts with fatty acids may be used. In case the soap has a pronounced alkaline reaction, this can be overcome, if objectionable, by the incorporation of alkali-neutraliz-ing ingredients in the preparation; or any

objectionable excess of alkali can be avoided in the manufacture of the shaving preparation. The adrenalin compounds incorporated with the preparation may react to a greater or less extent with certain of the ingredients of the shaving preparation, pro-
vided the reaction products also posses the de-sired styptic effect. 55

In addition to the styptic there may also be incorporated with the shaving preparation 60 antisepsics or other ingredients, including phenolic compounds other than the higher phenol-esters heretofore referred to. Com-pounds such as lysol or other phenols or phenolic compounds, metacresol acetate, para-chlor-meta-cresyl acetate, or other medicinal or antiseptic preparations can be used.

A convenient method of incorporating the adrenalin is in the form of an aqueous solu-tion, e. g. a solution containing 1 part adre-nalin to 1,000 parts of water, although a more concentrated solution can be used as well as a solution in some other solvent. Such a solu-tion may be incorporated into the shaving 70 cream, for example, in the proportions of 1 to 5 grams or centimeters of the solution per ounce of shaving cream. 75

While various shaving preparations may be made in various forms, I consider a shav-ing cream including the styptic as a particu-larly advantageous form of preparation. 80

In referring to a shaving preparation free from phenol-esters of higher fatty acids, I exclude such esters as are claimed in my com-pañion application heretofore referred to, 85 i. e., phenol-esters of fatty acids containing more than eleven carbon atoms.

Instead of adrenalin other suitable astringents or styptics can be used which are compatible with the ingredients of the shav-ing preparation, or other styptics or astringents can be used in addition to the adrenalin, etc., for example, tannin or tannin derivatives. 90

Adrenalin when used may be used in 95 various forms, including both natural and synthetic adrenalin products and including not only adrenalin itself, but adrenalin de-
rivatives of various kinds, or mixtures of adrenalin or combinations of adrenalin with 100

various other substances which do not interfere with the desired styptic action. Other ingredients such as perfumes, coloring material, antiseptics, etc. can be added. Also, preservatives or anti-oxidizing ingredients can be added to prevent objectionable oxidation or to improve the keeping qualities. When the shaving preparation is a cream it can be kept in tubes which protect it from oxidation and this is particularly advantageous with a styptic material which is liable to undergo oxidation unless preserved in some such way.

I claim:

- 15 1. A shaving preparation free from phenol-esters of higher fatty acids, and comprising a saponaceous material and an organic styptic compatible therewith.
- 20 2. A shaving preparation free from phenol-esters of higher fatty acids, and comprising a saponaceous material and adrenalin.
- 25 3. A shaving cream free from phenol-esters of higher fatty acids and containing adrenalin.

25 In testimony whereof I affix my signature.
NATHAN SULZBERGER.
